UNITED STATES PATENT OFFICE.

BENJAMIN BENNETT, OF JEANNETTE, AND HENRY SELLERS MCKEE, OF ALLEGHENY, PENNSYLVANIA.

DESIGN FOR A GLASS DISH.

SPECIFICATION forming part of Design No. 21,620, dated June 14, 1892.

Application filed January 18, 1892. Serial No. 418,506. Term of patent 14 years.

To all whom it may concern:

Be it known that we, BENJAMIN BENNETT, residing at Jeannette, in the county of Westmoreland, and HENRY SELLERS MCKEE, residing at Allegheny city, in the county of Allegheny, State of Pennsylvania, have invented a new and original Design for Glassware; and we do hereby declare the following to be a full, clear, and exact description thereof.

Our design relates to glass receptacles, such as glass dishes, jars, &c.; and it consists, generally stated, in a glass body or bowl having an annular horizontal flange passing out from the base thereof and feet extending down from said annular horizontal flange.

The accompanying drawing illustrates our design by a perspective view.

In the drawing the design is illustrated in connection with a pickle-jar having the body

portion *a*, which is to receive a cap, but which cap forms no part of the present design, said body portion having any desired surface ornamentation. An annular horizontal flange *b* passes out of the base of the said body portion, and extending down from the said horizontal flange are the feet *c*.

What we claim as our design, and desire to secure by Letters Patent, is—

The design for a glass dish, herein shown and described.

In testimony whereof we, the said BENJAMIN BENNETT and HENRY SELLERS MCKEE, have hereunto set our hands.

BENJAMIN BENNETT.
HENRY SELLERS MCKEE.
